UNITED STATES PATENT OFFICE.

JOSHUA NORTON, JR., OF CHATHAM, CANADA.

MACHINE FOR WASHING AND REDUCING WOOD PULP.

SPECIFICATION forming part of Letters Patent No. 495,262, dated April 11, 1893.

Application filed May 26, 1892. Serial No. 434,401. (No model.)

To all whom it may concern:

Be it known that I, JOSHUA NORTON, Jr., a resident of Chatham, in the Province of New Brunswick, Canada, have invented certain new and useful Improvements in Machines for Washing and Reducing Wood Pulp; and I do hereby declare the following to be a full, clear, and exact description of the invention, such as will enable others skilled in the art to 5 which it pertains to make and use the same.

The invention has for its object to provide efficient and economical apparatus for washing and reducing wood pulp and opening the same by separating its fibers and to effect 15 these purposes without breaking, disintegrating, or injuring said fibers.

In the accompanying drawings: Figure 1 is a plan of the improved apparatus. Fig. 2 is a partial section of a detail; and Fig. 3 a plan 20 of a pump fan, and Fig. 4 is a side elevation of the apparatus shown in Fig. 1.

Numeral 1 indicates a tank made preferably of two inch plank. A length of twenty feet and a width of four feet are suitable for 25 the body of the tank, though these dimensions may be greatly varied. Heretofore it has been usual to make the ends of pulp washing tanks rounded to avoid any bays or corners therein. A longitudinal partition 30 centrally placed and of less length than the tank has also been used to divide it into two parts through which in succession the charge of pulp was propelled by a beater roll or equivalent device, the curved ends being 35 necessary to avoid the lodgment of portions of the solid contents of the circulating charge. Such rounded ends and beater rolls are difficult and expensive to make and further the passages formed by the partition divide it 40 into two compartments of equal transverse area wherein the pulp moves with a uniform velocity. One of these passages serves no other purpose than to conduct the pulp to its starting point and to contain the propelling 45 devices. To avoid these rounded ends the tank, according to the present plan, is contracted as shown and provided with an outlet pipe or branch outlet 2, and an inlet conduit 3, both communicating with the main 50 conduit 20 the whole constituting a pulp circulating channel. The tank sides are parallel for the major part of the length of its

body. The sides toward the ends of the tank are inclined inwardly and have an angular relation to the parallel portions thereof. The 55 ends of the tanks consist of contracted portions having a transverse section much less than that of the tank body. Small pieces adapted to fill the angles at the ends 4 of the tank are indicated by 5.

60 6 denotes straps or plates to secure together the side and end planks.

8 indicates a water supply pipe provided with a suitable cock, and 9 indicates a vertically adjustable gate.

65 10 denotes a washer of usual construction adapted to permit the overflow of foul water through its reticulated walls and to discharge it into a trough 11, having a discharge-outlet governed by a valve or gate 11'. As many 70 washers may be employed as found desirable or convenient in practice. This washer extends transversely across the entire tank and to near its bottom.

75 12 indicates a driving pulley fast on a shaft 13, having bearings on the side walls of the tank. The washer is secured upon and revolved by this shaft.

The tank communicates through branch 80 outlet conduit 2 with a pump 14, of which 15 denotes the shaft, 16 the driving pulley and 17 the fans or wings. The pump shaft is extended on the side next the tank through the branch conduit 2 and also through the opposite wall of the tank in which it has a bearing 85 the other end having a bearing in the pump case. The fans of the pump are preferably slotted in substantially the manner represented. In the branch conduit 2 the shaft 15 is provided with spirally arranged beating 90 fingers 18.

The pump in the present instance opens upwardly into the bottom of the before mentioned main conduit 20. This conduit may consist of a metal tube about one foot in diameter.

95 21 is a shaft provided with teeth 22, which are adapted to be revolved between the teeth 23 fixed in the conduit wall. Said shaft has bearings in the closed ends of the conduit 20 and is provided with a driving pulley 24.

The dotted circles 25 indicate the inlet and outlet branches of the pulp circulating conduit communicating respectively with the

branches 2 and 3 and mediatly with the tank.

In operation the tank is charged with pulp and the pumps, pulp breakers and washer or washers put in motion by means of their several pulleys connected with a source of power in any convenient manner. The pump is arranged to draw the pulp from the tank and force it into the pulp circulating conduit and through said conduit back into the tank causing thereby a circulation of its contents. The pulp drawn into outlet pipe or conduit branch 2, is beaten and partially opened by the fingers fixed on the pump shaft extension. This action is rendered quite efficient by the comparatively small passage through the pipe and by the rapid movement of the shaft and teeth therein. The pulp is further beaten and opened by the pump fan the fingers of which are especially adapted for the dissociation of the fibers of the pulp. The loosening and separation of said fibers are further promoted by the beating and opening action of the fingers on shaft 21 which pass between those on the inner surface of the conduit. The teeth, whether of the shafts or of the fan beat the pulp without grinding its fibers against opposing surfaces, the spaces between such surfaces being made sufficiently large to obviate any tendency to break or grind the fibers as is the case in integrators, such as heretofore used in pulp washers. The construction described provides for the very rapid passage of pulp through tortuous passages, and for active beating of the same in pipe or conduit branch 2, and within the pump and in conduit 20. In the course of about twenty minutes these agencies will loosen up the pulp and dissociate its fibers, and thoroughly wash them. During the operation foul water is strained off and fresh water admitted. This admission takes place near the point where the pulp enters the branch conduit 2, whereby fresh water is

at once thoroughly intermingled with the pulp. The rapidity of the circulation is varied without altering the speed of the pump by means of the gate 9, while the gate 11' affords means for regulating the discharge of water through the sieve or washer. The comparatively small transverse dimensions of the circulating pipes and the consequent accelerated speed of the pulp and the repeated blows to which it is subjected combine to render the fiber-loosening action speedy and effective. And for this object the special form of pump fan is particularly well adapted as it provides for the drawing out and spreading of the pulp masses.

Having described my invention, what I claim is—

1. In combination the pulp washing tank 3, the pulp circulating conduit and pump, whereby pulp is drawn from the tank passed through the pump and returned to said tank, and a revolving shaft provided with beating fingers in said conduit; substantially as set forth.

2. In combination the pulp washing tank, the pulp circulating conduit made narrower than the tank and a pump, whereby pulp is drawn out of the tank passed through the conduit and pump and returned to said tank, the pump shaft being extended beyond the pump case into the conduit and provided with beating fingers in said conduit; substantially as set forth.

3. The combination of the pulp washing tank, circulating conduit and the pump, the fan of said pump having pulp dividing fingers; substantially as set forth.

In testimony whereof I have signed this specification in the presence of two subscribing witnesses.

JOSHUA NORTON, JR.
